SELF-LOADING PRESSURE ACCUMULATOR

Matthew W. Huber, Watertown, N. Y., assignor
to The New York Air Brake Company, a cor-
poration of New Jersey

Application March 8, 1948, Serial No. 13,647

2 Claims. (Cl. 103—223)

1

This invention relates to pressure accumulators and particularly to the type in which the loading pressure is developed by compressed air.

Such accumulators are used on airplanes and in other locations where light weight is a prime consideration. A separator between the gas of the cushion and the hydraulic liquid is necessary to prevent occlusion of gas in the liquid. Diaphragms have been tried, but are short-lived, so that a piston is generally accepted as the most satisfactory separator. Leakage of liquid (oil) past such a piston into the cushion space has been a source of trouble. So also has been loss of gas (usually air) from the cushion.

The present invention provides automatic means to maintain cushion pressure and purge any oil accumulating in the cushion, returning such oil to the sump of the hydraulic system.

The invention is applicable to any system having a gas-cushion accumulator, and having a pressure line which is alternately subjected to operating hydraulic pressure and a lower pressure. Usually the lower pressure is produced by venting the line.

According to the invention a hydraulically operated motor actuates a small compressor which charges the air cushion. The hydraulically operated motor makes one cycle each time the pressure line is loaded and then unloaded as it may be by a manually actuated control valve, or by an automatic unloading valve, to name two expedients well known in the hydraulic circuit art. Each such cycle delivers a small increment of air to the accumulator air cushion. At a desired maximum cushion pressure a loaded relief valve starts to bleed the air cushion. The relief valve is so located as to purge hydraulic liquid so long as any liquid is present in the air cushion, and in the absence of liquid to discharge excess air. In this way the cushion is kept up to pressure despite minor leakage, and is kept substantially free of liquid.

A preferred embodiment of the invention using one of many available pump-unloading valves will now be described by reference to the accompanying drawing.

Fig. 1 is a view partly in section and partly in diagram showing a hydraulic circuit including the self-loading accumulator.

Fig. 2 is a fragmentary view showing a modified pulsator-compressor.

A sump or reservoir 1 carries a supply of hydraulic liquid (usually oil) and delivers it through suction line 2 to a constantly running pump 3, here assumed to be a high speed displacement

2

pump capable of discharging into line 4 against back pressures of the order of 1500 p. s. i. or higher.

One branch of line 4 leads to the relief valve mechanism enclosed in body 5. This may assume various forms. The one chosen for illustration is a type developed by applicant's assignee, and not claimable per se herein since it is not the invention of the present applicant.

10 It need be described only briefly.

A unitary piston valve comprising a lower piston head 6, an intermediate valve head 7, and an upper piston head 8 is axially shiftable as a unit in a bore in body 5. In the lower position 15 of the valve, head 7 isolates pressure chamber 9 (connected with discharge line 4) from relief chamber 11 which is drained to sump 1 by line 12. In the upper position of valve head 7 the chambers 9 and 11 communicate freely.

20 Pressure chamber 9 communicates with pressure line 13 past check valve 14. This valve is lightly biased in a closing direction by a coil compression spring 15. Line 13, beyond valve 14 is in free communication with space 16 in housing 5 below piston head 6. Hence pressure in line 13 urges valve 7 in an opening direction, by reacting upward on piston head 6. The downward motion of valve head 7 is limited by a stop boss on the lower end of piston head 6, so that the closed position of valve head 7 is precisely defined.

25 The upper piston head 8 is formed with a flat on one side as indicated at 17. This offers restricted communication between chamber 9 and the space above piston head 8. Guided in a cylindrical bushing 18 is a valve plunger 19 which is in thrust relation with piston head 8, and is smaller in diameter than said piston head. Plunger 19 carries a spring-seat 21 and is biased downward by a coil compression spring 22 which reacts between spring-seat 21 and an adjustable spring-seat 23 threaded into a tubular extension of housing 5. In this way piston 6 and valve 7 are biased downward to valve-closed position, but the piston valve is hydraulically balanced except when the space above head 8 is vented.

30 The valve plunger 19 has a flat at 24 which extends only part way up one side of the plunger. When opened by upward motion of plunger 19, the vent passage so afforded has a larger flow capacity than that offered by the flat 17 on head 8 so that the pressures on heads 6 and 8 are unequal and the valve is forced up. A drain port 25 leads from the spring housing to chamber 11 and connection 12.

35 When pressure in line 13 is below a minimum

(here assumed to be 1200 p. s. i.) spring 22 holds plunger 19 and valve unit 6, 7, 8 down so that port 24 is closed. Pressure develops on the upper end of piston head 8 and the piston valve stays down so that head 7 isolates chamber 9 from chamber 11 and causes pump 3 to deliver past check valve 14 to line 13 instead of discharging to the sump past valve 7. At this time the pressure on the upper end of piston head 8 substantially balances that on the lower end of piston head 6. When the back pressure in chamber 9 reaches a value (here assumed to be 1500 p. s. i.) plunger 19 will have retreated far enough to expose flat 24, reducing the pressure on the upper end of piston head 8. Valve 7 is unbalanced and so quickly moves up and unloads pump 3. Check valve 14 immediately closes. When pressure later falls to the assumed low value of 1200 p. s. i. port 24 will again close whereupon the valve 7 will rapidly return to closed (loading) position.

Thus the unloading valve responds sharply to changes of pressure in line 13. In loading position line 4 is subject to pressures between 1200 and 1500 p. s. i. but in unloading position the pressure drops to nearly atmospheric.

The relief valve just described has outstanding operative characteristics for use with the self-loading accumulator, to be described. It unloads the pump completely. It shifts quickly between loading and unloading positions and has no tendency to stall in intermediate positions.

To steady the action of line 13 as a source of pressure fluid it is desirable to use an accumulator and one is shown connected to line 13. This comprises a cylinder 26 closed at its ends by heads 27 and 28 and subdivided by a floating piston 29 into a pressure liquid space 31 to which line 13 is connected and a gas cushion space 32.

To show some device as typical of those which may be fed by line 13, a valve generally indicated at 33 is connected to pressure line 13 and to an exhaust line 34. A handle 35 sets valve 33 to connect a motor 36 to supply line 13 or exhaust line 34 or disconnect it from both.

Gas cushion accumulators as heretofore constructed have given trouble because of loss of gas from the gas cushion space 32 and because of accumulation of hydraulic liquid in space 32, which occurs as a result of leakage past the piston.

To overcome these difficulties a pulsator type compressor is connected to be operated by the pressure changes in line 4 and deliver compressed gas (usually air) to cushion space 32.

A shouldered cylinder 37 is bored in head 28. When air is to be used as the cushion gas an inlet poppet valve 38 admits air from atmosphere. A discharge poppet valve 39 leads from the cylinder 37 to space 32. A plunger 41 is reciprocable in cylinder 37 and is biased in its suction direction by a coil spring 42 which reacts on a flange 40 smaller than the bore of the upper end of the cylinder. The outer (larger) end of the cylinder is closed by a head 43 and a branch of discharge line 4 leads to the outer end of the cylinder. Thus each time the pump 3 is loaded the plunger 41 makes a displacement stroke and each time the pump is unloaded the plunger 41 makes a suction stroke.

By keeping the compressor clearance small, and using a light return spring 42, the pulsator compressor can be made to deliver against a cushion pressure which is relatively high. Accumulator pressure is not as high as the maximum pressure reached in line 4. Plunger 41 makes its compres-

sion stroke just as the pump is loaded and consequently while the pressure in line 13 and in the accumulator is at its minimum value.

To vent any excess pressure fluid from the cushion space 32 a loaded relief valve 44 is used. By locating its entrance port at the very bottom of space 32 it acts to purge oil before it discharges gas. For this reason a connection 45 is made from the relief valve 44 to exhaust line 34, so that all liquid is returned to sump 1.

While the simple plunger 41 shown in Fig. 1 is satisfactory for all ordinary purposes, and provides a less expensive structure, I am aware that a pulsator compressor can be constructed to deliver against a pressure higher than that of the motive liquid. Such a unit is illustrated in Fig. 2.

The cylinder 137 is of two diameters and similar to cylinder 37. It is closed by head 143. A differential piston is used and comprises an air-displacing plunger 141 working in the smaller bore of the cylinder, and a motor piston 140 fitting the larger bore of the cylinder. The biasing spring 142 reacts against piston 140. The spring space is vented to atmosphere at 145. Air inlet and discharge valves are indicated at 138 and 139 respectively. Except that the pulsator piston is of the differential type the two constructions are substantially the same. They operate on the same principle.

Some general considerations will be stated to assure a correct understanding of the disclosure.

As a rule, the pressure maintained in an accumulator is much less than the maximum pressure developed by the pump. Cases are known where it is as low as one half of pump delivery pressure. It is this fact which makes the compressor motor of Fig. 1 usually adequate. Where high cushion pressures are desired they can be developed and maintained by using the arrangement shown in Fig. 2.

For illustrative purposes an automatic relief valve 5 is shown and is described in considerable detail. It typifies any means which will alternately cause pressure to be developed and dissipated in line 4. It is illustrated as the best known means, first because this particular valve is known to be automatic and certain in action, and second because its venting action is virtually complete. Obviously a hand operated vent valve could be used to secure the ultimate function of opening and closing a vent.

What is claimed is:

1. The combination of a liquid supply; a hydraulic pressure accumulator comprising an enclosing shell and a movable abutment dividing the space within said shell into a liquid space and a gas-cushion space, said shell also enclosing a pocket in communication with said gas space to which any liquid entering the gas space tends to flow by gravity; means for controlling the flow of liquid under pressure from the liquid space to a point of use; a constantly driven pump arranged to draw liquid from said supply and deliver it at higher pressure; a delivery connection from the pump discharge to said liquid space; a check valve interposed in said connection and serving to inhibit reverse flow therethrough; a normally closed valve operable to open and close a vent from the pump discharge in advance of said check valve; a motor compressor unit of the pulsator type, comprising a pulsator motor arranged to move in response to changes of pressure in said delivery connection occasioned by operation of said vent valve, and a compressor arranged to be actuated by motion of said motor

and connected to deliver compressed gas to said gas-cushion space; and a loaded relief valve controlling a vent path from said pocket and arranged to open in response to excess pressure to discharge liquid when present and gas at other times.

2. The combination of a liquid supply; a hydraulic pressure accumulator comprising an enclosing shell and a movable abutment dividing the space within said shell into a liquid space and a gas-cushion space, said shell also enclosing a pocket in communication with said gas space to which any liquid entering the gas space tends to flow by gravity; means for controlling the flow of liquid under pressure from the liquid space to a point of use; a constantly driven pump arranged to draw liquid from said supply and deliver it at higher pressure; a delivery connection from the pump discharge to said liquid space; a check valve interposed in said connection and serving to inhibit reverse flow therethrough; an unloader interposed in said connection between the pump and the check valve and serving in response to discharge pressure developed by the pump, to open and close a vent from the pump discharge in advance of said check valve as said pressure rises above a predetermined maximum

and falls below a predetermined minimum, respectively; a motor compressor unit of the pulsator type, comprising a pulsator motor arranged to move in response to changes of pressure in said delivery connection occasioned by operation of said unloader, and a compressor arranged to be actuated by motion of said motor and connected to deliver compressed gas to said gas-cushion space; and a loaded relief valve controlling a vent path from said pocket and arranged to open in response to excess pressure to discharge liquid when present and gas at other times.
